DANIEL W. TOWER, OF GRAND RAPIDS, MICHIGAN, ASSIGNOR TO GRAND RAPIDS BRASS COMPANY, OF GRAND RAPIDS, MICHIGAN, A CORPORATION OF MICHIGAN.

LATCH AND LOCK.

1,121,954.

Specification of Letters Patent. Patented Dec. 22, 1914.

Application filed June 1, 1914. Serial No. 842,214.

To all whom it may concern:

Be it known that I, DANIEL W. TOWER, a citizen of the United States of America, residing at Grand Rapids, in the county of 5 Kent and State of Michigan, have invented certain new and useful Improvements in Latches and Locks; and I do hereby declare the following to be a full, clear, and exact description of the invention, such as will 10 enable others skilled in the art to which it appertains to make and use the same.

This invention relates to an improved construction in latches and locks therefor, and more particularly to the same adapted to be 15 used in connection with swinging doors, and it is the object of this invention to provide a latch automatically operated by closing the door, and adapted to force the door open when manually opened, and to provide 20 the same with various novel and useful features as will more fully appear on understanding being had of the disclosure of a preferred embodiment of the invention illustrated in the accompanying drawing, in 25 which:—

Figure 1 is a front elevation of the latch applied to a door, a portion only of the door and casing therefor being shown; Fig. 2 is a side elevation with parts broken away and 30 in section to better disclose the construction; Fig. 3 is a side view of an element used in making the lock; Fig. 4 is a side view of the retaining member for the latch which is secured to the door casing; Fig. 5 is a plan 35 view of the locking plate, with associated parts in section; Fig. 6 is a view from beneath the locking mechanism and the housing therefor, showing the parts in assembled position; and Figs. 7 and 8 show in plan, in 40 two different positions, a movable disk element forming a part of the locking mechanism.

Like reference characters refer to like parts throughout the several views of the 45 drawing.

The latch, when in use, is applied to a swinging door adapted to close the opening in a casing, a portion of the casing adjacent the latch being shown at 1, and that 50 portion of the door to which the latch is secured being indicated at 2. In the construction of the latch, there is provided a

handle 3 integral with a cylindrical head 4, which head is mounted for pivotal movement in an outwardly projecting boss 5 integral with the housing 6 attached to the door 2. An arm 7 is also formed integral with the handle 3 and head 4 and extends from the head in a direction diametrically opposite the handle but with the end thereof 60 located closer to the door than is the handle. The head 4 is bored internally or may be cast in such manner that it is formed with a central interior cylindrical space from the inner end thereof to adjacent the outer end, 65 which end is partially closed having, however, an axial opening in which is journaled the outer end of pin 8 in the axis of the said head, and being slotted at 9 for the reception and guidance of a key for operating the 70 locking mechanism.

Fixedly attached to the inner end of the head 4 is a disk 10 substantially circular in outline except at one side thereof, an arm 11 integral with the disk extends through an 75 opening in the housing 6 adjacent the casing, the arm passing over the casing and in close proximity thereto when the handle 3 is moved into latching position. The arm 11 is bent inwardly and inclined to the plane of 80 the disk, forming in effect a cam surface for use as hereafter explained. In the side of the disk is a segmental recess, preferably extending about one fourth of the circumference of the disk and providing two 85 shoulders 12 and 13, as illustrated.

A locking plate 14 in the housing 6 is pivoted near one end to swing in its plane, being close to the disk 10 and having at one edge thereof and near the movable end, an 90 outwardly turned stop 15 which in one position of the locking plate is adapted to engage the shoulder 13, as shown in Fig. 8, and stop any movement of the disk in the unlocking direction, but which may be moved 95 so that the stop clears the disk entirely, permitting such movement. As a means of operating the locking plate, a key 16 may be inserted in the groove 9 of the pin 8 and through the opening 17 in the locking plate 100 14, the pin 8 passing therethrough also, and as the key is turned its edge will engage the flat sides of the opening in the plate, thus moving the plate back and forth between its

locking and unlocking positions, the key in effect working as an eccentric with its center of rotation at the axis of the pin 8, it, of course, being obvious that the device can-
5 not be locked except when the disk 10 has been properly positioned for the admission of stop 15 into the recess near the shoulder 13. To limit the pivotal movement of the disk and handle 3, there is provided a pro-
10 jection 18 fixed with relation to the housing 6 which projects into the recess of the disk 10 and by engagement with the shoulders 12 and 13 limits this movement; and with one shoulder 12 engaging the projection 18
15 and the stop 15 moved to engage the other shoulder 13, as indicated in Fig. 8, the disk will be held against any movement whatever, thus locking the handle 3 and arm 7.

Located immediately behind the locking 20 plate 14 is a triangular plate 19 which is fastened to the housing 6, preferably by screws inserted in bosses in the housing, as best shown in Figs. 2 and 6. The plate 19 has the members 20 cut and bent therefrom
25 to form friction springs engaging and slide-
able on the locking plate to prevent acci-
dental movement of the same after once be-
ing moved to a desired position.

A keeper 21 for the latch is attached to the 30 casing 1 and comprises an inclined retaining member 21^a, and a laterally extending lug 22 is provided at one side of the keeper 21 and located in the path of the arm 11. The arm 7 is adapted to engage the inner in-
35 clined surface of the member 21^a, so that as the handle 3 is turned to horizontal position, the door 2 will be forced to close contact with the casing. When the door is being closed, the arm 11 will engage the lug 22
40 and sliding on the same will automatically move the handle and arm 7, thus engaging the latter with the keeper member 21^a. And on returning the handle 3 to vertical position the arm 11 will slide over the lug 22,
45 thus starting the opening of the door should it tend to stick, as may be the case with tightly fitting doors used with refrigerators or similar structures.

From the foregoing the operating of the 50 device will be clear. The handle 3 has move-
ment from near the vertical position shown, until it is substantially horizontal, the arm 7 engaging the member 21^a and tightly closing the door 2. When the door is closing,
55 the arm 11 engages the lug 22 and automatically closes the latch. When in this po-
sition, the key 16 may be inserted and the stop 15 moved into the recess of the disk 10 and in the path of the shoulder 13, the
60 projection 18 engaging the other shoulder 12; the parts are thus locked against move-
ment. The unlocking of the latch is easily accom-
plished by the same key by moving the stop out of the recess, whereupon the handle
65 3 may be turned to vertical position and the

door partially opened as described, after which the door may be swung open as far as desired.

I have also shown a spring 23 attached at one end to a finger 24 projecting from the disk 10. When the handle is in vertical position, the direction of the pull of the spring is substantially through the center of rotation of the disk, there being little or no tendency for the disk to move under the influence of the spring. As the handle 3 is moved to horizontal position the spring force increases, thus automatically impelling the handle to a latching position and forcing the door closely against the casing. The spring thus aids in tightly closing the door but need not be used if not desired, as the device will operate quite well without.

The disclosure made is a preferred em-
bodyment of my invention, but it is to be
understood that the invention, defined in the
 appended claims, is comprehensive of all
 modifications of structure falling within
 their scope.

What I claim is:—

1. In a device of the character described, a housing adapted to be attached to a door, a handle pivoted in the housing, an arm extending opposite the handle, a keeper to be attached to a casing adjacent the door and adapted to receive the arm, locking mechanism within the housing to lock the arm and handle in fixed relation to the door and keeper and a removable key in the pivot of the handle adapted to operate the lock-
90 ing mechanism.

2. In a device of the character described, a housing adapted to be mounted on a door, a handle pivoted in the housing, means for limiting the movement of the handle to a predetermined arc, an arm extending opposite to the handle, a keeper for said arm adapted to be attached to a door casing, a lock located within the housing for locking the handle and arm in fixed relation to the door when at one extreme of their move-
95 ment and with said arm engaged with the keeper and a removable key in the pivot of the handle adapted to operate the locking mechanism.

3. In a device of the character described, a housing adapted to be attached to a door, a handle having at one end a cylindrical head rotative in the housing, a disk attached to the head and having a recess in the edge thereof, a projection in fixed relation to the housing and projecting into the said recess, an arm extending from the head opposite to the handle, and a keeper adapted to be secured to a casing and engaged by the arm.

4. In a device of the character described, in combination with a door and a casing, a housing secured to the door, a handle having a cylindrical head pivoted within a boss in the housing, an arm extending oppositely

from the handle and movable with the same, a keeper having an inclined surface to engage the arm, means for locking the handle and arm when the arm is engaged with the 5 said surface of the keeper and a removable key inserted in the axis of the head to operate the locking mechanism.

5. In a device of the character described, a handle, a housing, a tubular head integral 10 with the handle and rotative in the housing, an arm extending from the head oppositely to the handle, a disk within the housing and secured to the head, an arm extending from the disk through the housing, said arm being 15 inclined to the plane of the disk, and a fixed lug engaged by the arm.

6. In a device of the character described, a door and casing therefor, a housing attached to the door, a keeper secured to the 20 casing, a cylindrical head pivoted in the housing, a handle and arm oppositely extending from the head and integral therewith, a disk within the housing and secured to the head, means for locking the disk, an 25 arm on the disk inclined to the plane of the disk and extending through the side of the housing, a lug projecting from the keeper into the path of movement of said arm and a key in the axis of the head to 30 operate the locking means.

7. In a device of the character described, a housing adapted to be secured to a door, a head rotative in the housing and having a handle extending from and integral therewith, an arm projecting from the head, a keeper engaged by the arm, a disk fixed on the head, means for limiting the rotative movement of the disk, a spring attached to the disk and to the housing, said spring extending 35 across the center of the disk at one

limit of the movement of the disk and moving to a distance at one side thereof at the other limit of said movement.

8. In a device of the character described, in combination with a door and a casing, a 45 handle having a head pivotally mounted on the door, a keeper secured to the casing, an arm integral with the handle and adapted to engage the keeper, a disk fixed on the handle, means for locking the disk, a lug 50 projecting from the keeper, and an arm on the disk to engage said lug for moving the door toward the casing.

9. In a device of the class described, a 55 housing adapted to be attached to a door, a handle having a head rotative in the housing, an arm projecting from the head to engage a keeper to hold the door closed, means for locking the head, a key pin rotative in the axis of the head, and a key 60 adapted to be inserted in the pin to operate the locking means.

10. In combination with a door and a casing, a handle pivotally mounted on the door, an arm projecting from the handle, a keeper 65 on the casing having an inclined surface engaged by the arm, a second arm moving with the handle and having a surface inclined to the plane of its movement, and a fixed lug on the casing engaged by said 70 surface to automatically turn the first named arm into engagement with the keeper.

In testimony whereof I affix my signature in presence of two witnesses.

DANIEL W. TOWER.
